UNITED STATES PATENT OFFICE.

NEWTON L. SCHLOSS, OF NEW YORK, N. Y., ASSIGNEE OF ONE-FOURTH TO JOSEPH NORDEN AND ONE-FOURTH TO MORTIMER NORDEN, BOTH OF NEW YORK, N. Y.

ELEVATOR SIGNAL SYSTEM.

1,076,395.

Specification of Letters Patent.

Patented Oct. 21, 1913.

Application filed August 28, 1912. Serial No. 717,432.

To all whom it may concern:

Be it known that I, NEWTON L. SCHLOSS, a citizen of the United States, residing in the borough of Manhattan, city, county, and State of New York, have invented an Improvement in Elevator Signal Systems, of which the following is a specification.

Heretofore divers systems for signaling elevators have been adopted and used, as for example, elevator systems have been employed in which from any given floor in a building a signal could be transmitted to all the elevators in the elevator system in that building, and upon any given elevator approaching the floor from which the original signal was given, indicator lamps would be lighted; but in this system, the indicator lamps for several floors might be lighted by each car and if the different cars happened to be sufficiently close to one another, all the indicator lamps would be lighted, and consequently and with this particular system, there is such indefiniteness in the signals as to make it impossible for the person giving the original signal, to tell which car in the system will stop in response to his signal. So far as I am aware, such indefiniteness is also the case in all the signal systems which have heretofore been devised, and the object of my invention is to overcome this difficulty and provide an elevator signal system, in the use of which, a signal may be given on any floor of the building, which will indicate simultaneously in each of the cars in the system, from which floor the signal has been given. Devices are employed in each of the cars for simultaneously extinguishing the signal lamps which have been lighted in giving any signal, and signaling back to the floor from which the original signal was given, thereby indicating to the person giving this original signal, which car will stop. I may also employ devices making it possible for the party giving the original signal, to know that his signal has been transmitted to the various cars. The apparatus and electrical circuits for carrying out my invention will be herein-after more particularly described.

In the drawings, Figure 1 is a diagrammatical plan of the apparatus and electrical circuits for a given floor in a four-car elevator system. Fig. 2 is a side elevation of the annunciator relay employed in the elevator cars of the system. Fig. 3 is a front ele-

vation of the same. Fig. 4 is an elevation of the push button plate. Fig. 5 an elevation of the floor indicating lamp-box, and Fig. 6 is an elevation of the car annunciator, such as is employed in my improved elevator signal system.

Referring to the drawings, in carrying out my improved elevator signal system, I employ on every floor, as is usual, a push button plate indicated at 12, provided with the down push button 10, and the up push button 11. In this push button plate 12, preferably above and below the push buttons, I provide an opening fitted with a glass or other transparent plate, behind which respectively are located signal lamps 13 and 14.

On each floor and for each car in the system, I employ an indicator lamp box 15, above which in a suitable housing is a lamp 16, employed as an up-signal, and below which in a similar housing, is a lamp 17 employed for a down-signal. In each of the cars there is an annunciator 22 comprising a suitable casing, in the face of which there are series of corresponding openings fitted with glass or other suitable transparent material, behind which are located signal lamps 23 and 24, the lamps 23 being arranged in a vertical row, one for each floor as up-signals, and similarly the lamps 24 are arranged in a vertical row, employed as down-signals.

With each of the lamps 23 there is associated a pair of push buttons 25, 26, and similarly with each of the lamps 24 is associated a pair of push buttons, 27, 28. In connection with each lamp 23 and similarly with each lamp 24, I employ an annunciator relay 29, the push buttons 25 and 26 being adapted to operate,—that is,—to set the relay 29 associated with the lamp 23, and the push buttons 27, 28, to operate,—that is,—to set the relay 29 associated with the lamp 24.

On each floor and associated with the down-signal push button 10, I employ a cut-in relay 18 and a cut-out relay 19. Similarly on each floor and associated with the up-signal push button, I employ a cut-in relay 20 and a cut-out relay 21.

Referring particularly to Figs. 2 and 3, each of the annunciator relays preferably comprises a coil 29' with its core, which are secured to a bracket 30 fixed to the frame 31.

of the annunciator. Each of these relays is provided with an armature 32, carrying a knife-contact 33. Suitably connected to the bracket 30 and insulated from one another 5 and associated with each of these relays, are blade contacts 34 and 35, between which when the armature 32 is in its normal position as shown in Figs. 2 and 3, the knife-blade enters to close the circuit between the 10 same. Suitably connected to the bracket 30 of each annunciator relay is a T-lever 36, the pivot point being indicated at 37. The large arm of each of these T-levers is provided with a knife contact 38. Also associated with each of the annunciator relays 15 is a pair of blade contacts 39 and 40, which are suitably insulated from one another.

As hereinbefore described, each annunciator relay is also provided with push buttons 25 and 26. The push button 26 is connected 20 to a pin 41 on the interior of the annunciator casing and this pin 41 is adapted to bear against the right hand short arm of the T-lever, as shown in Fig. 3. Each annunciator relay is also provided with a rod 25 passing through and journaled in suitable lugs 43 and provided with a stop 44 and a spring 45 surrounding that portion of the stop 44 and the lower lug 43, so that normally the upper end of the rod 42 is maintained in positive contact with the underside of the right hand portion of the cross-arm of the T-lever.

The push button 25 is provided with a 35 pin 46 also within the casing of the annunciator and bearing against the upper surface of the left hand portion of the cross arm of the T-lever. This pin 46 preferably passes through a slotted opening in this cross- 40 arm of the T-lever, and between the shoulder thereon and the upper surface of the T-lever is fitted with a spring 47.

The parts of the annunciator relay are shown in their normal positions in Figs. 2 45 and 3. It will be understood however from the foregoing description, that by pressing the push button 26, the T-lever 36 may be rocked from the position shown in full lines in Fig. 3, to that shown in dotted lines. 50 This movement of the T-lever is imparted thereto against the action of the spring 45 pressing the rod 42 against the T-lever, thereby depressing the rod 42, causing the outer end thereof to contact with the armature 52, moving the same from the full line to the dotted line position and withdrawing the knife blade 33 from its position within the contact blades 44, 45, and at the same time the knife blade 38 is caused to enter and 55 make contact with the blade contacts 39 and 40.

It will be understood that the relay magnet may be reset by energizing the magnet and attracting the armature, thereby 60 returning the same to the full line position.

The movement of the armature transmitted through the rod 42 will swing the T-lever back to its full line position, and the T-lever may be moved from its dotted to the full line position, by pressing the push button 25, 70 which as will be understood, will open the electrical circuit at the blade contacts 39 and 40, the return of the armature to its full line position at the same time closing a circuit at the blade contacts 34, 35. 75

The electrical connections between the various parts of the apparatus hereinbefore described, in all probability can the better be explained in the description of the operation of the system, and this I will now 80 proceed to do, by reference to Fig. 1.

The line 48 may indicate the positive lead and the line 49 the negative lead from any source of electricity. The lead 48 is connected to one terminal of both the push buttons 10 and 11. Now assuming that a person is on the third floor and wishes to take a car going down,—the push button 10 is pressed, making a circuit between the contacts thereof. The second contact of this push button is connected by a wire 50 with the contact point 51. A wire 52 is also connected to the wire 50 and leads to one terminal of the cut in relay 18. The wire 53 is connected to the other terminal 90 of this cut-in relay 18 and to a wire 54 which is connected to the negative lead 49. It will therefore be seen that by pressing the push button, the circuit will be closed through the cut-in relay 18, by the wires 50, 95 52, 53 and 54 and the circuit will also be closed through the wires 55 and 56, connected across the terminals of the lamp 14. 100

By closing the circuit through the cut-in relay 18, the armature 57 thereof is attracted and makes contact with the contact point 51. The armature 57 coming into contact with this point 51, closes the circuits through the lamp 14 and through the down-annunciator lamp corresponding to the third floor in every car in the elevator system,—these circuits being as follows:—

By way of the positive lead 48, the wire 58, the armature 59 of the cut-out relay 19, the contact point 77, the wire 60, the 115 armature 57 of the cut-in relay 18, the contact point 51, the wire 50, the wire 55, lamp 14, wire 56, to the negative lead 49, and also from the wire 50, through the wire 61, to the wires 62, to the contact points 34, 35, 120 through the lamp 23 in car No. 1, wire 64, wire 65, wire 66, to the junction point 67 connected to the wire 68, returning to the negative lead 49. Also by the wires 69 and 70 through the corresponding lamp in car 125 No. 2, through the wires 71 and 72, and the corresponding lamp in car 3, and through the wires 73 and 74 and the corresponding lamp in car 4. It will therefore be seen 130 that the signal has been given in each car,

indicating that there is a passenger on the third floor who wishes to descend. Further that the lighting of the lamp 14 will indicate to the person giving the signal that the circuit has been closed to the lamps in the cars, thereby indicating that this signal has been transmitted to each car in the system.

It is noted here that the circuit is normally opened at the armature 57 of the cut-in relay 18 and normally closed at the armature 59 of the cut-out relay 19. It will also be understood that the operator in one of the cars,—generally the one nearest the floor from which such a signal has been received,—is to answer the signal.

In the present explanation, it will be assumed that car No. 1 is nearest the third floor, and that the operator of car No. 1 answers this signal, which he has received, and in so doing, the operator presses the press button 26 of the annunciator lamp in his car corresponding to the third floor, thereby swinging the T-lever from its normal position as shown in Figs. 2 and 3, to the dotted line position and in so doing, the circuit to the lamp in car No. 1 corresponding to the third floor down, is opened at the contact plates 34, 35, and another circuit is closed through the contact blades 39, 40, by the knife contact 38. This circuit which is closed at the contact blades 39 and 40, is as follows:—From the positive lead 48 through the wire 58, the cut-out relay 19, the wire 75, through the lamp 17, the wire 76, the contact point 40, contact point 39, the wire 65, wire 66, wire 68, to the negative lead 49. It will therefore be seen that in closing this circuit, the operator in car No. 1 has signaled back to the floor from which the original signal was given, indicating that this is the car which will stop there. At the same time by closing the circuit through the cut-in relay 19, the circuit hereinbefore described through the other annunciator lights in all the other cars of the system, has been opened by the armature 59 of the cut-out relay being attracted and breaking the circuit at the contact point 77. This of course indicates to the operator of the other cars that the signal from floor No. 3 has been answered and therefore need not be given their attention.

The lamp 17 continues to burn until car No. 1 has stopped at floor 3 and by the stopping of the car, or the opening of the door thereof, a contact may be made in any suitable manner between the shoe 78 and a line 79, which closes a circuit through the annunciator relay in car No. 1 corresponding to the third floor. This circuit is through the shoe 78, wire 79, to the coil of the up-annunciator of floor No. 3, through the wire 80 to the coil of the down-annunciator in car No. 1 for floor 3, and through the wire 81, the wire 66, the wire 68, return-

ing to the negative lead 49. The closing of this last named circuit resets the down-annunciator for floor 3 in car No. 1 which has been operated, and in so doing opens the circuit to the down signal lamp on floor No. 3.

The circuits for operating the up-signals are similar to those hereinbefore described for the down-signals. Taking as an illustration, the first car and a signal given from the third floor. It may be assumed that a person on this floor desires to take the car going up. The push button 11 is then actuated, closing the contacts thereof and making a circuit from the positive lead 48 through the wire 82 to the contact point 83 and through the wire 84 to the cut-in relay 20 from this relay, by the wire 54 to the negative lead 49. This circuit being closed through the magnet of the relay 20, energizes the same and causes the armature 85 thereof to be attracted to contact with the point 83. This closes a circuit through the up-annunciator lamps for floor 3 in every one of the cars. This circuit is as follows: From the positive lead 48, through the wire 58, the wire 86; the armature 87, the cut-out relay 81, the contact point 88, the wire 89, the armature 85 of the cut-in relay 20, the contact 83, the wire 82, the wire 90, the wire 91, through the contact points 92, 93, of the relay corresponding to the up-signal lamp for floor 3 in car 1, (it being understood that the contact points 92, 93, correspond with the contact points 34, 35, as hereinbefore described) through the lamp 24, the wire 65, wire 66, wire 68, to the negative lead.

It will also be apparent that the circuit is closed through the up-signal lamp for the third floor in each of the other cars:—in car 2 by the wires 94 and 70; in car 3 by the wires 95 and 72, and in car 4 by the wires 96 and 74.

Now obviously the operator in each car has received the signal that someone on floor 3 wishes to take a car going up. Assuming for example, as was assumed before,—that car No. 1 is now going up and is the nearest car to the third floor. The operator of car No. 1 then presses the button 26 of the annunciator for the up-signal lamp for floor 3, thereby swinging the armature from the contact points 92, 93, breaking the circuit thereat, and at the same time making a circuit between the contact points 97 and 98. Making the circuit at these contact points closes the following circuit through the up-indicator lamp 16 on floor 3:—From the positive lead 48, wire 58, wire 86, through the cut-out relay 21, wire 99, indicator lamp 16, wire 100, contacts 97, 98, wire 65, wire 66, wire 68, to the negative lead 49. Opening the annunciator lamp circuit at the contacts 92, 93, causes the lamp 24 in car 1 to go out and by closing the cir-

cuit through the contact points 97, 98, the cut-out relay 21 is energized causing the armature 87 thereof to break the annunciator light circuit at the contact point 88, thus extinguishing the annunciator lights in all the other cars. The indicator lamp 16 remains lighted until the car stops at the third floor to take on the passenger.

In opening the car door to receive the passenger, or by other means, the circuit is closed by the contact shoe 78 as hereinbefore described, which circuit includes the annunciator relays for the lamp for floor 3 in car 1, whereby the relay which has been actuated is automatically reset, and in being reset opens the circuit to the up signal lamp on floor No. 3.

It will be obvious that the wiring for every floor must be similar to that hereinbefore described for floor 3 and that the system may be used in any building where any required number of elevators are employed.

I claim as my invention:

1. An elevator signal system comprising a push button on each floor, an indicating signal lamp on each floor for every car, an annunciator signal lamp for each floor in every car, means operative upon actuating a push button on any floor for closing a circuit to an annunciator lamp in every car, means operative in every car for opening the circuit so closed and simultaneously closing the circuit to the indicating lamp on the floor on which a push button was actuated, and means operative when the car is stopped at any floor in response to the signal for opening the circuit through the said indicating signal lamp.

2. An elevator signal system comprising a push button on each floor, an indicating signal lamp on each floor for every car, an annunciator lamp for each floor in every car, means operative upon actuating a push button for closing a circuit to an annunciator lamp in every car, a lamp at the push button, which is lighted when the push button is actuated and also when the aforesaid circuit is closed through the annunciator signal lamps, means operative in every car for opening the circuit so closed and simultaneously closing the circuit to the indicating lamp on the floor on which the push button was actuated, and means operative when the car is stopped at any floor in response to the signal for opening the circuit through the said indicating signal lamp.

3. An elevator signal system comprising a push button on each floor, an indicating signal lamp on each floor for every car, an annunciator signal lamp in every car for each floor, a cut-in relay for each push button, a circuit closed through a cut-in relay by actuating the corresponding push button, a circuit closed through an annunciator signal lamp of every car by the armature of the

said cut-in relay, means in every car for opening the circuit through the annunciator lamps and simultaneously closing the circuit through the indicating lamp on the floor where the push button was operated, and means operative when the car is stopped at any floor in response to the signal for opening the circuit through the said indicating lamp.

4. An elevator signal system comprising a push button on each floor, an indicating signal lamp on each floor for every car, an annunciator signal lamp in every car for each floor, a cut-in relay for each push button, a circuit closed through a cut-in relay by actuating the corresponding push button, a circuit closed through an annunciator signal lamp of every car by the armature of the said cut-in relay, means in every car for opening the circuit through the annunciator lamps and simultaneously closing the circuit through the indicating lamp on the floor where the push button was operated, means operative when the car is stopped at any floor in response to the signal for opening the circuit through the said indicating lamp, 90

5. An elevator signal system comprising a push button on each floor, an indicating signal lamp on every floor for each car, an annunciator signal lamp in every car for each floor, a cut-in relay for each push button, a circuit closed through a cut-in relay by actuating the corresponding push button, a circuit closed through the annunciator signal lamps in all the cars by the armature of the said cut-in relay, a circuit for each indicating signal lamp, devices for the said annunciator signal lamps in each car which when operated in any given car, open the circuit through the annunciator signal lamp in that car and simultaneously close the circuit to the indicating lamp corresponding to that car on the floor on which the button is operated and also open the circuit to all corresponding annunciator lamps in the other cars, and means operative when the car is stopped at any floor in response to the signal for opening the circuit through the said indicating signal lamp.

6. An elevator signal system comprising an up and a down push button on each floor, an up and a down signal indicating lamp on each floor for every car, an up and a down annunciator signal lamp in every car for each floor, means operative upon actuating the down push button on any floor for closing the circuit to the corresponding down annunciator lamp in every car, means operative upon actuating the up push button on any floor for closing the circuit to the corresponding up annunciator lamp in every

car, means operative in every car for opening the circuit so closed and simultaneously closing a circuit to the corresponding indicating signal lamp on the floor at which either of the said push buttons was actuated.

7. An elevator signal system comprising an up and a down push button on each floor, an up and a down signal indicating lamp on each floor for every car, an up and a down annunciator signal lamp in every car for each floor, means operative upon actuating the down push button on any floor for closing the circuit to the corresponding down annunciator lamp on every car, means operative upon actuating the up push button on any floor for closing the circuit to the corresponding up annunciator lamp in every car, means operative in every car for opening the circuit so closed and simultaneously closing a circuit to the corresponding indicating signal lamp on the floor at which either of the said push buttons was actuated, and means operative when the car is stopped at any floor in response to the signal for opening the circuit through the said indicating signal lamp.

8. An elevator signal system comprising an up and a down push button on each floor, an up and a down signal indicating lamp on each floor for every car, an up and a down annunciator signal lamp in every car for each floor, means operative upon actuating the down push button on any floor for closing the circuit to the corresponding down annunciator lamp in every car, means operative upon actuating the up push button on every floor for closing the circuit to the corresponding up annunciator lamp in every car, means operative in every car for opening the circuit so closed to the down annunciator lamps and simultaneously closing a circuit to the down indicating signal lamp on the floor at which the down push button was actuated, and means operative in every car for opening the circuit so closed to the up annunciator signal lamps and simultaneously closing the circuit to the up indicating signal lamp on the floor at which the up push button was actuated.

9. An elevator signal system comprising an up and a down push button on each floor, an up and a down signal indicating lamp on each floor for every car, an up and a down annunciator signal lamp in every car for each floor, means operative upon actuating the down push button on any floor for closing the circuit to the corresponding down annunciator lamp in every car, means operative upon actuating the up push button on every floor for closing the circuit to the corresponding up annunciator lamp in every car, means operative in every car for opening the circuit so closed to the down annunciator lamps and simultaneously closing a circuit to the down indicating signal lamp on the floor at which the down push button was actuated, and means operative in every car for opening the circuit so closed to the up annunciator signal lamps and simultaneously closing the circuit to the up indicating signal lamp on the floor at which the up push button was actuated.

10. An elevator signal system comprising an up and a down push button on each floor, an up and a down signal indicating lamp on each floor for every car, an up and a down annunciator signal lamp in every car for each floor, means operative upon actuating the up push button on any floor for closing the circuit to the corresponding up annunciator lamp in every car, means operative in every car for opening the circuit so closed and simultaneously closing the circuit to the up indicating signal lamp on the floor at which the up push button was actuated, and means operative when the car is stopped at any floor in response to the signal for opening the circuit through the said indicating signal lamp.

11. An elevator signal system comprising an up and a down push button on each floor, an up and a down signal indicating lamp on each floor for every car, an up and a down annunciator signal lamp in every car for each floor, means operative upon actuating the down push button on any floor for closing the circuit to the corresponding down annunciator lamp in every car, means operative upon actuating the up-push button on every floor for closing the circuit to the corresponding up-annunciator lamp in every car, a lamp at the up push button, which is lighted when the circuit through the up annunciator signal lamps is closed, a lamp at the down push button, which is lighted when the circuit through the down annunciator signal lamps is closed, means operative in every car for opening the circuit so closed to the down annunciator lamps and simultaneously closing a circuit to the down indicating signal lamp on the floor at which the down push button was actuated, means operative in every car for opening the circuit so closed to the up annunciator signal lamps and simultaneously closing the circuit to the up indicating signal lamp on the floor at which the push button was actuated, and means operative when the car is stopped at any floor in response to the signal for opening the circuit through the said indicating signal lamp.

12. An elevator signal system comprising an up push button for every floor, a down push button for every floor, an up indicating lamp for every floor, a down indicating lamp for every floor, an up annunciator lamp and a down annunciator lamp for each floor in every car, an annunciator relay for each annunciator lamp, a cut-in relay and a cut-out relay for the up push button on every floor, a cut-in relay and a cut-out relay for the down push button on every floor, a circuit for each up annunciator lamp in every car, which circuit is normally open at the armature of the corresponding up cut-in relay and closed at a contact made by the armature of the corresponding cut-out relay, and is also normally closed by the armature of the corresponding up annunciator relay in every car, a circuit from each up annunciator lamp in every car to the corresponding up indicator lamp, and in which circuit is the corresponding up cut-

out relay, a device associated with each up annunciator relay, which when actuated opens the circuit to its and the other corresponding up annunciator lamps, and simultaneously closes the circuit to the corresponding up indicator lamp through the corresponding up cut-out relay, thereby lighting said up indicator lamp and opening the circuit to all the corresponding annunciator signal lamps, a circuit for each down annunciator lamp, in every car, which circuit is normally opened at the armature of the corresponding down cut-in relay and closed at a contact made by the armature of the corresponding down cut-out relay, and is also normally closed by the armature of the corresponding down annunciator relays in every car, a circuit for each down annunciator lamp in every car to the corresponding down indicator lamp, and in

which circuit is also the corresponding down cut-out relay, a device associated with each down annunciator relay which, when actuated, simultaneously opens the circuit to its and the other corresponding annunciator lamps and closes the circuit to the corresponding down indicator lamp through the corresponding down cut-out relay, thereby lighting the said corresponding down indicator lamp and opening the circuit to all the corresponding down annunciator lamps, and means for resetting the said devices associated with the said annunciator relays, and simultaneously opening the circuit to an indicator lamp. 25 30 35
